UNITED STATES PATENT OFFICE

110,246

DESIGN FOR A THERMOMETER

Lurelle Guild, Darien, Conn., assignor to Weston
Electrical Instrument Corporation, Newark,
N. J., a corporation of New Jersey

Application December 2, 1937, Serial No. 73,320

Term of patent 7 years

To all whom it may concern:

Be it known that I, Lurelle Guild, a citizen
of the United States, residing at Darien, county
of Fairfield, State of Connecticut, have invented
a new, original, and ornamental design for a
Thermometer, of which the following is a speci-
fication, reference being had to the accompany-
ing drawing, forming part thereof, and wherein:

Fig. 1 is a front elevation of the thermometer,
showing my new design;

Fig. 2 is a side elevation of the same; and
Fig. 3 is a side elevation with parts shown in
section.

I claim:

The ornamental design for a thermometer, as
shown.

LURELLE GUILD.
